DAVID BENSON, OF NANUET, NEW YORK.

Design No. 3,231, dated November 10, 1868.

DESIGN FOR A WELL-CURB.

The Schedule referred to in these Letters Patent and making part of the same.

To all whom it may concern:

Be it known that I, DAVID BENSON, of Nanuet, in the county of Rockland, and State of New York, have invented a new and original Design for Well-Curb; and I do hereby declare that the following is a full, clear, and exact description thereof, which will enable others skilled in the art to make and use the same, reference being had to the accompanying photograph, forming part of this specification.

This invention relates to a new and original design for a well-curb, which is clearly shown in the accompanying photograph.

A is the base of the curb, of rectangular-square form, and having upon it the lower part B of the curb, which part is provided, at each side of its top, with a bead or moulding, and at each angle or corner with a bead, b, a recess, b^x, being in the front side of the part B, for the discharge of water.

On the top of the part B of the curb, at three sides

thereof, there is an open wire-work panel, C, and above these panels there is a cap, D, having a moulding, d, at each side.

The panel at the front of the part B of the curb is open, with the exception of a bracket, a^x, at each side.

The cap D has a double-pitch roof, with concave sides, E E, and ornamental pendants, e, extending all around it.

There is an upright ornament, f, on the top or peak of the roof, with an upright ornament, g, at each end.

Having thus described my invention,

I claim as new, and desire to secure by Letters Patent—

The within-described design for a well-curb, substantially as set forth and shown.

DAVID BENSON.
